UNITED STATES PATENT OFFICE.

JOHN V. BELL, OF CLIFTON, NEW JERSEY.

BELT BUCKLE.

Application filed March 29, 1926. Serial No. 98,348.

The present invention is concerned with the provision of an improved belt buckle of the plate type, in which the anchored end of a belt is secured in concealed position under the plate, and the free end of the belt is adapted to be adjustably clamped under the plate.

One object of the invention is to provide a buckle of this general character which is equipped with means for engaging a button or clasp upon the trousers of a wearer in such a manner that circumferential movement of the belt, as well as vertical movement of the buckle is prevented, and the buckle will always be retained in properly centered position at the front of the waistband of a pair of trousers.

A further object of the invention is to provide a unique mechanism which serves both to clamp the anchored end of the belt, and to adjustably secure the running or free end thereof.

Other objects of the invention are to provide a belt buckle embodying the above noted features, which will be of simple, practical construction, rugged, durable and efficient in use, capable of ready attachment to the anchored end of a belt adapted to securely and conveniently clamp the free end of a belt, a buckle which will be of attractive appearance, and one which may be manufactured with comparative economy.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a view in longitudinal section through a buckle embodying the present invention showing the same engaged with a belt. The dotted lines in this figure indicate a pair of trousers and a button thereon engaged by the buckle.

Fig. 2 is a view in rear elevation of the buckle with the belt straps attached.

Figs. 3 and 4 are perspective views of the two co-operating clamping elements.

Fig. 5 is a view in side elevation of the assembled clamping elements showing them in position to receive the end of the strap to be anchored.

In the drawings I have used the reference

character 10 to indicate the belt plate or body formed with the usual angularly disposed lateral flanges 11 which co-operate with the plate to define a belt receiving channel. The end of the belt to be anchored has been indicated by the reference character 12, and the free or running end thereof by the reference character 13.

A feature of the invention is the provision of a pair of co-operating clamping elements illustrated in Figs. 3 and 4, and designated generally by the reference numerals 14 and 15. It will be noted that the clamping member 14 includes a front plate portion 14^a formed with a pair of side flanges 16. The flanges at one end are formed with projecting apertured ears 17 which extend beyond the plate 14^a, the ears 17 receiving a pivot bar 18 extending transversely under the plate 10 and mounted in the flanges 11. Near its other corner, and spaced a greater distance from the plate 14^a than the openings in the ears 17, are a pair of aligned openings 19 adapted to receive trunnions 20 on the clamping element 15.

It will be noted that the clamping element 15 is also in the nature of a plate which is transversely compoundly curved, defining a substantially flat intermediate portion 21 carrying at one end the trunnions. An angularly disposed set of teeth or spurs 22 are turned down from the corner of the plate 21 adjacent the trunnions, and the other edge of the plate 21 curves into an oppositely facing tail piece 23 formed with a bevelled biting edge 24.

In Fig. 4 I have illustrated the member 15 swung to proper position to receive the anchored end 12 of the belt, and in this figure it will be noted that the member 15 has been swung through approximately 180°, so that the teeth 22 are turned away from the plate 14^a, and permit the free insertion of the belt end 12 between the members 14 and 15. In order to permit such swinging movement of the member 15, it is necessary to swing the member 14 on its pivot 18 so that the member 15 may swing clear of the belt plate 10.

Having inserted the belt end, the member 15 is swung to the position of Fig. 1, thereby rotating the teeth 22 into biting engagement with the end of the belt 12. As the belt is placed about the body of a wearer, the free end 13 thereof is inserted under the plate 10 and passed between the plate and the tail

piece 23 of the clamping element 15. It will be understood that with the belt end 12 anchored by the clamping pieces 14 and 15, these clamping pieces act as a unit, and the belt 13 may be freely drawn under the plate since this action on the tail piece 23 will be to swing the two members 14 and 15 of the clamping unit on the pivot 18 away from the plate. Any retrograde movement of the free end 13 of the belt, however, simply serves to bring the clamping unit into firmer engagement therewith, and to clamp the free end firmly between the clamping unit and the under face of the plate 10. This will be apparent from Fig. 1 wherein it will be noted that attempted movement of the belt end 13 to the left, will act on the tail piece 23 to swing the clamping unit on the pivot 18 toward the under face of the plate 10. Or in other words, into clamping engagement with the belt end 13. Thus, in order to release the end 13 of the belt, it is necessary to manually swing the clamping unit 14, 15 away from the plate 10 and withdraw the end of the belt.

Another feature of the invention is the provision of means for engaging a button on the trousers or waistband of a garment to prevent either vertical or circumferential movement of the belt. I have illustrated means for accomplishing this purpose, which includes a flat transverse bar 25 formed with ears 26 pivoted on studs 27 carried by the flanges 11 of the buckle plate. Integral with the bar 25 are a pair of fingers 28 adapted to embrace a button indicated in dotted lines at 29 as attached to a garment 30. It will be noted that the length of the fingers 28 is such

that they engage with the pivot bar 18. The manner of use of the button engaging member 25, 28 is to swing it on its pivots 27, move the fingers 28 into button embracing position, and then manually effect relative pivotal movement of the member 25, 28 and the belt plate 10 until the free ends of the fingers 28 engage the pivot bar 18. Vertical movement of the belt will then be limited by the fingers 28, and circumferential movement thereof, by the distance between the bar 18 and the inner end of the slot 28^a defined by fingers 28.

It will also be apparent that instead of engaging a button, the buckle might be readily engaged with a clasp on a pair of trousers or under one of the flaps of the fly.

While I have illustrated one of the preferred embodiments of the invention, various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claim.

I claim:

A belt buckle including a buckle plate and flanges thereon, a cross bar pivoted between the flanges and carrying fingers adapted to straddle a button or the like on a garment, and a second bar under the buckle plate co-acting with the fingers to prevent retraction of such button from the end of the slot defined by the fingers.

JOHN V. BELL.
